GEORGE A. WEBER, OF NEW YORK, N. Y., ASSIGNOR TO THE WEBER RAILWAY JOINT MANUFACTURING COMPANY, OF NEW YORK, N. Y., A CORPORATION OF WEST VIRGINIA.

RAIL-JOINT.

SPECIFICATION forming part of Letters Patent No. 739,466, dated September 22, 1903.

Application filed February 10, 1903. Serial No. 142,730. (No model.)

To all whom it may concern:

Be it known that I, GEORGE A. WEBER, a citizen of the United States, and a resident of the borough of Manhattan, city, county, and 5 State of New York, have invented certain new and useful Improvements in Rail-Joints, of which the following is a specification, accompanied by drawings.

My invention relates to rail-joints, but 10 more particularly to stepped joints, or such as are formed at the junction of rails of different sizes or weights; and the objects of my invention are to improve upon the construction of such joints.

15 Further objects of my invention will hereinafter appear; and to these ends my invention consists of a rail-joint for carrying out the above objects embodying the features of construction, combinations of alinement, 20 and arrangement of parts, substantially as hereinafter fully described in this specification and shown in the accompanying drawings, in which—

Figure 1 is a side view, partly in section, 25 of a rail-joint embodying my invention. Fig. 2 is a plan view of the same. Fig. 3 is a horizontal sectional view of the joint on the line $y-y$ of Fig. 1. Fig. 4 is a transverse sectional view of the joint on the line $z-z$ of Fig. 1 30 looking in the direction of the arrow. Fig. 5 is a transverse sectional view of the joint on the line $x-x$ of Fig. 1 looking in the direction of the arrows. Fig. 6 is a detailed end view of two rails of different size and 35 weight arranged with the running-surfaces in alinement and the bases of the rails substantially parallel with each other. Fig. 7 is an enlarged detailed side view of a portion of a channeled plate, showing the offsets on the 40 same. Fig. 8 is a transverse sectional view of fish-plates shown in Fig. 7. Fig. 9 is a top view of the portion of fish-plate shown in Fig. 7. Fig. 10 is a side view of a modified form of a joint.

45 Referring to the drawings, A and B represent the meeting ends of rails of different size and weight to be connected by a suitable rail-joint. In the detailed end view of Fig. 6 the conditions to be met are clearly illustrated, it being seen that supports of different height must be provided for the rails and

the difference in the positions of the parts of the rails are to be compensated for in the rail-joint, or, in other words, the difference in position of the remaining parts when the 55 inner faces of the heads of the rails in alinement are to be compensated for.

The rail A is shown as being of greater height than rail B and having a thicker flange and broader head, although various combinations of rails may be joined by suitable joints—as, for instance, the rails shown in Fig. 10, in which the rail C is of less height than the rail D, but has a thicker head, and consequently the modification of the joint is 60 shown in this instance. A suitable support is provided for the rail ends, shown in this instance as a rail-chair E, having an upright F and base portion G. Bearings of different height are provided upon the base portion G, 65 whereby the running-surfaces of the rails may be supported in surface. I have shown a simple and efficient form of stepped support for the rail ends consisting of transversely-extending cleats or bearing-blocks H 70 upon a portion of the rail-chair. These cleats or blocks H are suitably secured to the chair, in this instance they being shown as riveted to the base portion of the chair by rivets I, and according to my construction 75 each cleat or block is riveted at a portion only of its length to a rail-chair. In this instance each cleat is provided with but one rivet I, the inner ends J of the cleats abutting against the upright F of the rail-chair, 80 so that movement of the cleats longitudinally 85 of the chair is prevented.

The rail B of lesser height appears upon the cleats or supports H, of which there may be any suitable number, while the rail A 90 bears directly upon the support or chair E, and the fish-plates secured at each side of the rail ends are adapted to compensate for differences in the position of the parts of the rails. The fish-plates are adapted to bear 95 upon the flanges K of the rails and also upon the inner portions L of the heads of the rails, and in order to accomplish this end it will be seen that each fish-plate is offset at the top and bottom, the offset O of one fish-plate 100 compensating for the differences in the thickness of the heads of the rails and the offset

P compensating for the differences in the height of the rails. Since the webs of the rails are not of the same thickness, it will be seen that additional compensation is provided therefor, each fish-plate being offset laterally as well as at the top and bottom.

While any suitable form of fish-plate may be provided, I have shown flanged fish-plates, one in the form of a flanged plate Q and the other in the form of a channel-plate R, while a filling-strip, which may be of wood, is inserted in the channel of the plate R and between the plate and the upright F of the rail-chair E. Suitable bolts T are adapted to secure the parts of the joint-flanges together, and since the fish-plates bear upon the flanges of each rail and also beneath the inner portions of the heads of the rails it will be seen that a tight and rigid joint is formed. In the construction shown the edge of a flange of a fish-plate lies in substantially one plane and the edges of the flanges of the channel-plate lie in substantially the same plane. In forming the fish-plates with the requisite offsets, both lateral and at the top and bottom, any suitable means may be used; it having been found convenient to forge the fish-plates with the requisite offsets. In the modification shown in Fig. 10 the rail C of lesser height has the thicker head, and therefore the flanged fish-plate is forged or otherwise formed with the requisite offsets to meet the conditions required in a joint of the character shown in Fig. 10. As before, the fish-plate bears upon the flanges of each rail and upon the inner portions of the heads of the rails, so that when the bolts are tightened up a firm and rigid joint is secured.

I do not herein claim the rail-joints shown, described, and claimed in my copending application, Serial No. 154,220, filed April 25, 1903, for improvements in step-joints.

Obviously some features of my invention can be used without others, and my invention may be embodied in widely-varying forms.

Therefore, without limiting myself to the construction shown and described or enumerating equivalents, I claim, and desire to obtain by Letters Patent, the following:

50 1. The combination with rails of different size and height, of a rail-support adapted to keep the running-surfaces of said rails in alinement, fish-plates offset both laterally and at the top and bottom to compensate for differences in position of the remaining parts when the running-surfaces of the heads of said rails are in surface and alinement, for substantially the purposes set forth.

60 2. The combination with a stepped rail-chair adapted to keep the running-surfaces of rails of different height in surface and alinement, of channel and angle plates, both offset laterally and at top and bottom to compensate for differences in position of the rails when in position on the chair, for substantially the purposes set forth.

3. The combination with the rail ends, of a rail-chair having an upright and a base portion, said base portion being stepped to afford bearings of different height for the rail ends, channel and angle plates both offset laterally and at top and bottom to compensate for differences in position of the rails when in position on the chair, a packing-strip inserted between the channel-plate and the upright of the rail-chair, and bolts for securing the parts of the joint together, for substantially the purposes set forth.

4. The combination with rails of different size and height, of a stepped rail-support adapted to support the running-surfaces of said rails in surface and alinement, fish-plates offset both laterally and at top and bottom to compensate for differences in position of the remaining parts when the inner faces of the heads are in alinement, the said fish-plates being adapted to bear upon the flanges and the under portions of the heads of the rails, and means for securing the parts of the joint together, for substantially the purposes set forth.

5. The combination with rails of different size and height, of a rail-support having cleats or bearing-blocks upon a portion of the same, whereby the running-surfaces of said rails of different height may be supported in surface and alinement, for substantially the purposes set forth.

6. The combination with rails of different size and height, of a rail-chair having an upright and a base portion, transversely-extending cleats or bearing-blocks secured to the base of the rail-chair on a portion of the same, whereby the running-surfaces of said rails of different height may be supported in surface and alinement, for substantially the purposes set forth.

7. A fish-plate for a stepped rail-joint characterized by a lateral offset and an offset at both top and bottom to compensate for differences in position of rails of different height and size, for substantially the purposes set forth.

8. A flanged fish-plate for a stepped rail-joint characterized by a lateral offset and an offset at both top and bottom, the flanged edge lying in substantially one plane, for substantially the purposes set forth.

9. A channeled fish-plate for a stepped rail-joint characterized by a lateral offset and an offset at both top and bottom, the edges of the flanges of the channel lying in substantially the same plane, for substantially the purposes set forth.

In testimony whereof I have signed this specification in the presence of two subscribing witnesses.

GEORGE A. WEBER.
